UNITED STATES PATENT OFFICE

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

HEAT-ECONOMIZER.

1,329,767.

Specification of Letters Patent.

Patented Feb. 3, 1920.

Original application filed December 8, 1914, Serial No. 876,011. Divided and this application filed November 20, 1918. Serial No. 263,305.

To all whom it may concern:

Be it known that I, DAVID S. JACOBUS, a citizen of the United States, residing in Jersey City, in the county of Hudson and State of New Jersey, have invented certain new and useful Improvements in Heat-Economizers, of which the following is a specification.

My invention relates to an economizer and more particularly to a high pressure economizer of the form shown in my prior application, Ser. No. 876,011, which was filed in the Patent Office, Dec. 8, 1914, of which the present application is a division, said prior application having become U. S. Letters Patent No. 1,289,182, which was issued December 31, 1918.

My present invention relates more particularly to the economizer construction in which boxes or headers are arranged in rows within the economizer flue and connected by rows of economizer tubes inclined to the horizontal and secured in the headers, the latter being spaced apart sufficiently to permit of the ends of the tubes being placed therebetween in order to insert the same in the headers or remove the same therefrom.

In accordance with my invention the gases are made to travel in a downward direction over the tubes of the economizer, and the flow of water through said tubes is in general in the reverse direction of the flow of the gases.

My invention will best be understood by reference to the accompanying drawings, in which Figure 1 is a rear view of an economizer embodying my invention, and Fig. 2 a detailed view showing the vent connection between the boxes of Fig. 1.

The economizer embodying my invention and which will usually be of the high pressure type, is shown as consisting of a series of rows of tubes 25 expanded into horizontal boxes or headers 26, and as having a slight inclination upward in the direction of flow of the water. The tubes and boxes are preferably of wrought iron or wrought steel to withstand the high boiler pressure to which this stage of the economizer is subjected. The inlet pipe 22 enters the lowermost of the headers 26, as shown in Fig. 1, and by said header is distributed

to the tubes of the lowermost row. The water then flows through the successive rows of tubes, from side to side, as indicated by the arrows, until it leaves through pipe 27 by which it is delivered to the steam and water drum. The described flow of the water through the high pressure stage of the economizer provides for a positive circulation, and the passage through tubes all of which are inclined upward with reference to the direction of flow of the water. This causes any air or non-condensable gases which may not have been removed from the water in the gas liberating tank through which the water passes before reaching the economizer to be carried along with the general current and out of the economizer. It also allows of a construction which can be readily relieved of air on being filled with water from an empty state. The positive circulation of water through the high pressure stage is also of great advantage in causing a maximum amount of heat absorption from the gases.

The horizontal boxes or headers 26 of each row are spaced apart so that the tubes may be replaced by passing them between two of the boxes and into the hole in the box on the opposite side of the economizer. The tube is slipped in some distance through the box on the opposite side, then brought opposite the hole in the other box to which it is to be connected, and then drawn back to the proper position. Another advantage of the construction is that the hand-hole fittings opposite the tube ends for use in expanding the tubes may be made smaller than where the tubes are passed through the hand-hole fittings, thus making it possible to construct a stronger box from the same thickness of material. Again, a single hand-hole fitting may be employed for expanding two or more of the tubes, the expander being introduced through such hand-hole fitting. Where the hand-hole fittings do not admit the use of an expander with a straight shank, a jointed expander may be employed. Another way of expanding the tubes is to use a jointed expander passed through hand-hole fittings in the ends of the boxes, in which case only as many hand-hole fittings need be provided in the sides of the boxes.

as are desired for assisting in the manipulation of the jointed expander and for inspecting the tube ends. Replacing the tubes in the way described is advantageous also in making it possible to set the boilers and economizers nearer together, that is, with less aisle room, than where the tubes are replaced through the hand-hole fittings. Should the tubes be replaced through the ordinary form of hand-hole fittings, the aisle width would have to be such that the full length of a tube could be introduced at right-angles to the boxes, whereas with the arrangement described the tubes may be moved sidewise between the boxes and introduced at an angle.

Still another advantage of this arrangement relates to cleaning the tubes. Owing to the boxes being spaced apart from each other in the rows and a space being left in the separating bricks or material which may be used between the boxes, a steam or air lance may be inserted between the boxes either through special openings or through the doors 27 shown on Fig. 1. Such steam or air lance will serve to blow off the soot and collection on the economizer tubes.

In Fig. 2 I have shown, on an enlarged scale, the manner of connecting the boxes 26 to prevent the pocketing of air in the upper part of the boxes and to permit its escape to the uppermost box. As there shown, the connection consists of a relatively small vent pipe 26' extending from the top of one box to near the top of the box directly above it. As so arranged the air or gases must flow all the way along each one of the boxes before it can enter the vent pipe connection leading to the box directly above it, thus preventing short circuiting of the water without the removal of the air, and causing air from the lowermost boxes to sweep through the full length of all of the upper boxes, which leads to the removal of any air bubbles which might otherwise lodge at certain points in the upper sides of the boxes. Naturally, some of the air will pass through the economizer tubes through being carried along with the general current of water as previously described, the action of the small vent pipe 26' being supplemental to this. In Fig. 2 I have also indicated hand-hole fittings 26² in the sides of the boxes for expanding the tube ends to make a tight joint. Each hand-hole fitting serves for the expansion of three tube ends, a jointed expander being used. I have also shown hand-hole fittings 26³ in the ends of the boxes through which a jointed expander may be introduced for expanding the tubes.

The described economizer is especially applicable to conditions where steam may be generated in the economizer. This feature will be useful in connection with waste heat work where the ratio of the work done in

the economizer and the boiler varies a considerably greater amount than in coal fired boiler furnaces. In a waste heat boiler the initial temperature of the gases may for a time be over 2000° F. The temperature of the gases may then fall to, say, approximately 1000° F., with the same, or even a greater, weight of gas flowing through the boiler per hour as existed with the higher temperature. When a large volume of gas flows through the boiler and economizer at a low temperature, the relative amount of work done by the economizer, in proportion to that done by the boiler, is such that, if the economizer is designed to give the best results with the high temperature gases, steam will be formed in the economizer with the low temperature gases. With the arrangement shown of the high pressure stage of the economizer, any steam formed therein will not have as great a tendency to carry over slugs of water as in some other forms of economizers.

What I claim and desire to secure by Letters Patent of the United States is:—

1. An economizer having oppositely located headers arranged in rows, tubes connecting said headers so as to present an unobstructed passage for the gases, the headers of each row being spaced apart sufficiently to allow the tubes to be passed between the headers for insertion, each header having a series of hand-holes and each hand-hole serving a plurality of tube holes.

2. An economizer having oppositely located headers arranged in rows, tubes connecting said headers so as to present an unobstructed passage for the gases, the headers of each row being spaced apart, the spaces between the headers and the interior economizer structure being arranged to allow the tubes to be passed in between the headers and introduced in place into the tube holes.

3. An economizer comprising a flue for the passage of gases, headers arranged in rows within said flue and at opposite sides thereof, tubes connecting said headers so as to present an unobstructed passage for the gases, the headers of each row being spaced apart, the spaces between the headers and the interior economizer structure being arranged to allow the tubes to be passed in between the headers and introduced in place into the tube holes.

4. An economizer having substantially horizontal headers arranged one above the other through which the water is successively circulated, and having relatively small vent connections extending from the top of one header to the header directly above it.

5. An economizer having oppositely located headers arranged in rows, tubes connecting said headers so as to present an unobstructed passage for the gases, vent con-

nections leading from near the top of one header to the box directly above said first header, said vent connections being so arranged that the air and gases must flow all the way along each one of the headers before it can enter the vent connection leading to the box which comes directly above it.

In testimony whereof I have hereunto signed my name in the presence of two subscribing witnesses.

DAVID S. JACOBUS.
